METHOD AND APPARATUS FOR SETTING
PRINTING INKCarl P. Mann, Riverton, N. J., assignor, by
mesne assignments, to Interchemical Corpora-
tion, New York, N. Y., a corporation of Ohio

Application December 30, 1937, Serial No. 182,435

22 Claims. (Cl. 101—416)

This invention relates to printing and aims to provide improved apparatus for setting printing ink.

There are so-called "quick-drying" inks on the market at present containing solvents which are non-volatile at ordinary press room temperatures (25° C.) and which become highly volatile liquids at about 150° C. Such inks are dried and set by causing the material upon which they have been printed to travel through a furnace where the printed surface of the material is subjected to heat of such great intensity that the solvent is volatilized instantly and solvent vapors are burned in the furnace. Such furnaces are heated by means of a series of gas burners fixed to manifolds mounted within the furnace through which fuel consisting of a mixture of gas and air is supplied to the burners. These burners have not been operated at maximum efficiency in the past because it has been necessary to supply an excess of air in the fuel mixture to support combustion of the vapors of the ink solvent within the furnace. Furthermore, the heat to which the burner manifolds are subjected in the furnace causes them to become dangerously hot.

I have discovered that the burners of a furnace may be operated at maximum efficiency to supply the intense heat required to dry a quick-drying ink and, at the same time, combustion of solvent vapors may be supported within the furnace and the fuel supply manifolds for the burners within the furnace may be prevented from becoming too hot.

In carrying out my method, printing ink containing a volatilizable inflammable solvent is dried by moving the material past a heater provided with a gas burner directed toward the printed surface of the material. A substantially completely combustible mixture of gas and air is burned in the heater, volatilizing the solvent of the ink and burning the solvent vapor. The heater is cooled and air is provided for combustion of the solvent vapor by projecting a current of air over the heater and then into admixture with the solvent vapor.

My invention includes also apparatus by means of which the heater is cooled and air necessary to support the combustion of solvent vapors is supplied while the burners of the heater are operating at maximum efficiency.

In accordance with my invention, an enclosed furnace is located in the path of printed material as it emerges from the printing press. An air duct communicates with the interior of a furnace which contains a heater adapted to direct intense

heat upon the printed surface of the material and means are provided for distributing air from the air duct over the part of the printed surface which is adjacent the heater.

A specific embodiment of the apparatus for carrying out my invention is illustrated in the accompanying drawings in which:

Fig. 1 is a side elevation of the furnace attached to the frame of a printing press;

Fig. 2 is a plan view of the furnace; and

Fig. 3 is an elevation of the air duct.

In the apparatus illustrated in the drawings, ink is applied to a web of material 6 by means of an ordinary web press 7. The material 6 emerges from the press with its printed surface uppermost and travels, in the direction indicated by the arrows, through the furnace and over rollers 8, 9, 10 and 11 to rewind roller 12. The furnace through which the printed material 6 travels is enclosed in a casing of insulating material 14 attached to the frame of the printing press 7 and is supplied with heat through a series of burners 15 fixed to manifolds 16 which extend across the interior of the furnace and communicate with a fuel chamber 17. Fuel is supplied to the respective burners 15 from their manifolds 16 by needle valves 18. The burners 15 are contained in a compartment 19 which is separated from the compartment 20 containing manifolds 16 by strips of insulating material 21 having slits 22 between their adjacent edges.

The end of the furnace which is adjacent press 7 is equipped with end plate 24 and a narrow opening 25 through which the printed material 6 enters the burner compartment 19 of the furnace. A suction duct 26, provided with damper 27, communicates with the burner compartment 19 of the furnace at its other end and communication between the suction duct and manifold compartment 20 is prevented by the member 28.

A controlled amount of fresh cool air is supplied to the manifold compartment 20 of the furnace: A row of conduits 30 and a row of conduits 31, which communicate with manifold compartment 20, project from end plate 24 into a tapered air duct 32 attached to that end plate. The larger end of air duct 32 communicates with blower 33 and is provided with a damper 34.

As the printed material 6 travels through the burner compartment 19 of the furnace, its printed surface is subjected during a very brief period to heat from burners 15 of sufficient intensity to volatilize the solvent of the ink and ignite the solvent vapor. At the same time, fresh cool air is supplied from blower 33 to the manifold com-

partment 20 of the furnace. The taper of air duct 32 effects a uniform distribution of air from blower 33 to conduits 30 and 31 extending into that air duct, and it will be noted that the diameter of the conduits 30 in the upper row is larger than the diameter of the conduits 31 in the lower row, thus insuring circulation of fresh, cool air over burner manifolds 16 to the far end of the furnace. After the air from duct 32 passes over 10 the burner manifolds 16, it flows through slits 22 to the burner compartment 19 where it is distributed over the printed surface of the material 6 adjacent the burners 15. The air from duct 32 not only cools manifold 16, but, in passing down 15 through slits 22, counteracts the tendency of gases contained in the burner compartment 19 to rise to the manifold compartment 20, and the distribution of this air over the printed surface of the material 6 supports combustion of the solvent 20 vapors within the burner compartment 19 of the furnace, permitting the burners 15 to be operated at maximum efficiency.

Gases, which include products of combustion and any solvent vapors which may not be burned, 25 are withdrawn from burner compartment 19 through suction duct 28. The amount of air supplied to the furnace through air duct 32 is controlled by damper 34, and the rate at which 30 gases are withdrawn from the burner compartment 19 is controlled by damper 27 in suction duct 28. The adjustments of these dampers will vary with the material printed, the rate at which it 35 is printed, etc., and can best be effected by observing conditions within the furnace. The fresh air damper 34 is most desirably adjusted so that the tail of the flames caused by combustion of the solvent vapors appears to travel along the surface of the material 6 at a speed which is substantially the same as the speed of that material. Suction damper 27 is most desirably 40 opened to a point just beyond that at which products of combustion are observed to cease traveling over roller 8.

What I claim is:

45 1. The method of drying a printing ink containing a volatilizable inflammable solvent after the ink has been printed upon material, which comprises moving the material past a heater provided with a gas burner directed toward the 50 printed surface of the material, burning a substantially completely combustible mixture of gas and air in said heater, volatilizing the solvent of the ink, projecting a current of air over said heater and then into admixture with the solvent vapor to cool the heater and provide air for combustion of the solvent vapor, and burning said 55 solvent vapor.

2. The method of drying a printing ink containing a volatilizable inflammable solvent after 60 the ink has been printed upon material, which comprises moving the material through an enclosed heater provided with a gas burner directed toward the printed surface of the material, burning a substantially completely combustible mixture of gas and air in said burner, volatilizing the solvent of the ink, projecting a current of air over said heater and then into admixture with the solvent vapor to cool the heater and provide air for combustion of the solvent vapor, and burning said solvent vapor.

3. The method of drying a printing ink containing a volatilizable inflammable solvent after 65 the ink has been printed upon material, which comprises moving the material through a furnace 70 provided with a gas burner directed toward the

printed surface of the material, burning a substantially completely combustible mixture of gas and air in said burner, volatilizing the solvent of the ink, projecting a current of cool air through said furnace and then into admixture with the solvent vapor, and burning said solvent vapor.

4. The method of drying a printing ink containing a volatilizable inflammable solvent after 10 the ink has been printed upon material, which comprises moving the material through a furnace containing a gas burner directed toward the printed surface of the material, burning a substantially completely combustible mixture of gas and air in said burner, volatilizing the solvent of the ink, projecting a stream of cool air through 15 the furnace and then into admixture with the solvent vapor, burning the solvent vapor in the furnace, and then withdrawing the products of combustion from the furnace.

5. The combination with a printing press, of 20 an enclosed furnace located in the path of the printed material, a heater mounted in said furnace and adapted to direct intense heat upon the printed surface of the material, an air duct communicating with the interior of the furnace, and 25 means for distributing air from said duct over the part of said printed surface which is adjacent said heater.

6. The combination with a web printing press, 20 of an enclosed furnace located in the path of the printed web, a heater mounted in said furnace and adapted to direct intense heat upon the printed surface of the web, an air duct communicating with the interior of the furnace, and means for distributing air from said duct over the part 35 of said printed surface which is adjacent said heater.

7. The combination with a printing press, of 40 an enclosed furnace located in the path of the printed material, a gas burner mounted in said furnace and adapted to direct intense heat upon the printed surface of the material, an air duct communicating with the interior of the furnace, and means for distributing air from said duct over the part 45 of said printed surface which is adjacent said gas burner.

8. The combination with a printing press, of 50 an enclosed furnace located in the path of the printed material, a heater mounted in said furnace and adapted to direct intense heat upon the printed surface of the material, an air duct 55 communicating with the interior of the furnace, means for distributing air from said duct over the part of said printed surface which is adjacent said heater, and a suction duct communicating with the interior of the furnace.

9. The combination with a printing press, of 60 an enclosed furnace located in the path of the printed material, a heater mounted in said furnace and adapted to direct intense heat upon the printed surface of the material, an air duct adapted to deliver fresh air into the interior of the furnace, means for regulating the amount of air delivered from said air duct to the furnace, and means for distributing the air delivered from 65 said duct over the part of said printed surface which is adjacent said heater.

10. The combination with a printing press, of 70 an enclosed furnace located in the path of the printed material, a burner manifold mounted in said furnace, a gas burner fixed to said manifold, an air duct adapted to deliver cool air to the interior of the furnace, and means for causing the cool air delivered from said duct to circulate 75 around said burner manifold.

11. The combination with a printing press, of an enclosed furnace located in the path of the printed material, a burner manifold extending across the interior of said furnace, a series of 5 gas burners fixed to said manifold and adapted to direct intense heat upon the printed surface of the material, an air duct adapted to deliver cool air to the interior of said furnace, means for circulating the cool air delivered from said 10 duct around said burner manifold, and means for distributing said air over the part of said printed surface which is adjacent the gas burners.
12. The combination with a printing press, of 15 an enclosed furnace having a manifold compartment and a separate burner compartment located in the path of the printed material, a gas burner mounted in said burner compartment and adapted to direct intense heat upon the printed 20 surface of said material, an air duct adapted to deliver cool air to said manifold compartment, and means for distributing said air over the part of said printed surface which is adjacent said heater.
13. The combination with a printing press, of 25 an enclosed furnace located in the path of the printed material, a heater mounted in said furnace and adapted to direct intense heat upon the printed surface of the material, an air duct, a plurality of conduits extending from the interior of the furnace into said air duct, and means for distributing air delivered to the furnace through said conduits over the part of said 30 printed surface which is adjacent said heater.
14. The combination with a printing press, of 35 an enclosed furnace located in the path of the printed material, a heater mounted in said furnace and adapted to direct intense heat upon the printed surface of the material, a tapered air duct, a blower connected with the larger end of said air duct, a row of conduits extending from the interior of the furnace into said air duct, and means for distributing air delivered to the furnace through said conduit over the part of said 40 printed surface which is adjacent said heater.
15. The combination with a printing press, of 45 an enclosed furnace having a manifold compartment and a separate burner compartment located in the path of the printed material, a gas burner mounted in said burner compartment and adapted to direct intense heat upon the printed surface of said material, an air duct, a plurality of conduits extending from the manifold compartment into said air duct, and means for distributing air delivered to the manifold compartment through 50 said conduits over the part of said printed surface which is adjacent said gas burner.
16. The combination with a press for printing upon a traveling material, of an enclosed furnace located in the path of the printed material and having an opening for the entrance of said material, a heater mounted in said furnace and adapted to direct intense heat upon the printed surface of the material, an air duct communicating with the interior of the furnace adjacent said entrance opening, and means for distributing air from said duct over the part of said printed surface which is adjacent said heater.
17. The combination with a press for printing 55 upon a traveling material, of an enclosed furnace having an entrance opening and an exit opening located in the path of the printed material,
- a heater mounted in said furnace and adapted to direct intense heat upon the printed surface of the material, an air duct communicating with the interior of the furnace adjacent said entrance opening, means for distributing air from said duct over the part of said printed surface which is adjacent said heater, 60 a suction duct communicating with the interior of the furnace adjacent said exit opening, means for circulating air from said suction duct over the part of said printed surface which is adjacent said heater, and a duct for directing air from said suction duct into said furnace adjacent said exit opening.
18. The combination with a printing press, of 10 an enclosed furnace located in the path of the printed material, a plurality of burner manifolds extending across the interior of said furnace, a series of gas burners fixed to said manifold and adapted to direct intense heat upon the printed 15 surface of the material, an air duct adapted to deliver cool air to the interior of said furnace, means for circulating cool air delivered from said duct around said burner manifolds, and means for distributing said air over the part of said 20 printed surface which is adjacent the gas burners.
19. The combination with a web printing press, of a furnace having an entrance opening and an exit opening located in the path of the printed 25 web, a plurality of burner manifolds extending across the interior of the furnace between said openings, a series of gas burners fixed to said manifolds, an air duct adapted to deliver cool air to the interior of the furnace adjacent the entrance opening, and a suction duct communicating 30 with the interior of the furnace adjacent the exit opening.
20. The combination with a web printing press, of a furnace having an entrance opening and an exit opening located in the path of the printed 35 web, a plurality of burner manifolds extending across the interior of the furnace between said openings, an air duct adapted to deliver cool air to the interior of said furnace adjacent the entrance opening, a suction duct communicating 40 with the interior of said furnace adjacent the exit opening for withdrawing gases from said furnace, means for regulating the amount of air delivered to the furnace through said air duct, and means for regulating the quantity of gases withdrawn 45 from the furnace through said suction duct.
21. The combination with a press adapted to print an ink containing a volatilizable inflammable solvent upon a traveling web, of an enclosed heater adapted to subject the printed surface of the traveling web to heat of sufficient intensity to volatilize the solvent of the ink and burn the solvent vapor, and means for directing a stream of air through said heater and then into admixture with the solvent vapor to cool the 50 heater and provide air for the combustion of said vapor.
22. A method of drying a printing ink containing a volatilizable inflammable solvent after the ink has been printed upon material, which 55 comprises moving the material past a heater provided with a gas burner directed toward the printed surface of the material, burning a substantially completely combustible mixture of gas and air in said burner, volatilizing the solvent 60 of the ink, projecting a current of air over said burner with at least a portion thereof passing into admixture with the solvent vapor so as to cool the burner and provide air for combustion of the solvent vapor, and burning said solvent 65 vapor.

CARL P. MANN.
